UNITED STATES PATENT OFFICE.

MICHAEL CHERNOW, OF BROOKLYN, NEW YORK.

DESIGN FOR AN ESCUTCHEON MONOGRAM PLATE.

Application filed June 2, 1928. Serial No. 26,975. Term of patent 7 years

To all whom it may concern:

Be it known that I, MICHAEL CHERNOW, a citizen of the United States and residing at Brooklyn, in the county of Kings and State of New York, have invented a new, original, and ornamental Design for an Escutcheon Monogram Plate, of which the following is a specification, reference being had to the ac-

companying drawings, forming part hereof.

Figure 1 is a plan of the monogram escutcheon plate.

Figure 2 is an edge view of the plate.

I claim:

The ornamental design for an escutcheon monogram plate as shown.

MICHAEL CHERNOW.
